UNITED STATES PATENT OFFICE.

SAMUEL MICHAUD, OF ROSEBURG, OREGON.

COMB.

Application filed February 16, 1923. Serial No. 619,473.

To all whom it may concern:

Be it known that I, SAMUEL MICHAUD, a citizen of the United States, and resident of Roseburg, in the county of Douglas and 5 State of Oregon, have invented certain new and useful Improvements in Combs, of which the following is a specification.

My invention relates to improvements in combs, and it consists in the combinations, 10 constructions and arrangements herein described and claimed.

An object of the invention is to improve the construction of combs having detachable teeth so as to provide a comb of simplified 15 construction, the teeth of which can be readily removed to facilitate cleaning thereof or to permit replacement of broken or deformed teeth.

A further object of the invention is to 20 provide a comb of the character described which is inexpensive to manufacture and thoroughly practical commercially.

Other objects and advantages will be apparent from the following description, considered in conjunction with the accompanying drawings, in which—

Figure 1 is a view showing in side elevation a comb embodying the invention with portions thereof broken away and other portions shown in section,

Figure 2 is a section along the line 2—2 of Figure 1, and

Figure 3 is a perspective group view showing different elements of the comb detached from one another.

In carrying out the invention, I provide a plurality of teeth, two of which are different from the remaining teeth and are adapted to be arranged at the ends of a 40 series containing all the teeth, and a back including means for engaging the teeth to removably hold them in parallel aligned relation.

As illustrated in the drawings and shown 45 to advantage in Figure 3, the back comprises a holder or frame designated generally at 1 and a cover or cap plate 2. The holder or frame 1 comprises a pair of elongated side plates or strips 3 and 4 respectively which are held in spaced parallel relation by transverse strips which connect the upper edges of the side strips at the opposite ends thereof and by ends as indicated at 5 and 9, respectively, in Figs. 1 and 3. 55 The side plates or strips 3 and 4, the connecting strips 5, and the ends 9, are prefer-

ably integral with one another and the lower edge portions of the side plates 3 and 4 are offset inwardly to define shoulders 3^a and 4^a at a determined height above the plane of 60 the lower edges of the side plates and preferably being inclined. The side plates 3 and 4 are bent or turned inwardly along 65 their lower edges as indicated at 3^b and 4^b respectively.

The end teeth comprised in the device are indicated at 6 and the intermediate teeth are designated 7. The end teeth 6 are exactly alike and the overall length of each is less than that of each of the intermediate 70 teeth 7. Each end tooth 6 has integral shank and head portions, the head portions having straight sides reduced at 6^a to provide shoulders adapted to rest upon the shoulders 3^a and 4^a of the side strips of the 75 holder when the upper end of the head is in contact with the underside of one of the connecting strips 5. The head of each end tooth 6 is further reduced at its juncture with the shank portion thereof, as indicated at 6^b to 80 provide shoulders resting upon the inwardly extending edge portions 3^b and 4^b of the side strips of the holder.

The intermediate teeth 7 likewise include 85 head and shank portions, each head portion being reduced in width to define shoulders 7^a adapted to rest upon the shoulders 3^a and 4^a of the side strips or plates of the holder and being further reduced in width at the juncture thereof with the shank portions as 90 indicated at 7^b to conformably engage the inwardly extending edge portions of the side strips or plates. The intermediate teeth 7 have the head portions thereof of greater 95 thickness than the shank portions to define opposite shoulders 7^c—7^d at the upper ends of the shanks, each shoulder 7^c being preferably rounded or arcuate for a purpose to be hereinafter set forth. The head portion of each end tooth 6 is of greater thickness than 100 the shank and extends at one side laterally of the corresponding side of the shank to provide a shoulder 6^c, the face of which is arcuate in contour to conform to the contour of each of the shoulders 7^c.

The teeth 6 and 7 are placed in the holder 1 between the side strips or plates 3 and 4 with the end teeth 6 at the ends of the holder in underlying relation to the connecting strips 5. The intermediate teeth 7 110 are interposed between the two end teeth so that all the teeth are in aligned parallel

relation. Since the intermediate teeth 7 are identical in construction, the shank portions thereof which project from the holder will be spaced apart and the shoulders 7^c at proximate sides of adjacent teeth will cooperate to provide a bottom or end wall for each opening or space between two adjacent teeth. The shoulder 6^c of each end tooth will likewise cooperate with the proximate shoulder 7^c of the adjacent intermediate tooth to provide an end wall for the one end space between an end tooth and the adjacent intermediate tooth. Since the shoulders 6^c and 7^c are arcuate in contour, the end wall of the space between two adjacent teeth is arcuate throughout its length and in consequence no sharp corners are provided to engage with strands of hair drawn therethrough or to provide a lodging place for dirt and foreign matter. The inwardly turned edges of the side plates 3 and 4 contact the teeth along a line lying substantially in a plane tangent to the shoulders 6^b and 7^b, whereby strands of hair drawn through the spaces between the teeth will slide freely over the edge portions of the holder and will not be caught between the holder and the teeth. Moreover the engagement of the holder with the teeth renders more difficult the passage of dirt or like matter between the holder and the teeth.

The cover or cap has a body 8 which is of channel formation and is adapted to slidably fit the holder 1 with the teeth held in the latter in the manner described, the flanges 8^a—8^a of the cap or cover being adapted to straddle the relatively wide upper portions of the side plates 3 and 4 and having inwardly turned lower edge portions 8^b—8^b adapted to engage the outer faces of the shoulders 3^a and 4^a to releasably hold the cap or cover upon the holder 1 in the position shown in Figures 1 and 2. The cap or cover is made of a material having spring qualities so that the flanges thereof will closely engage with the side strips of the holder when the cap or cover has been slid along the holder to the position illustrated in Figures 1 and 2.

The flanges on the body 8 incline inwardly or are beveled at their ends, as indicated at 8^c to facilitate removal and replacement of the cap or cover upon the holder. The ends 9 of the holder engage the remote walls of the end teeth 6 and prevent movement of the series of teeth longitudinally of the holder while at the same time preventing the passage of dust and other extrinsic matter between the heads of the teeth and the cover.

From the foregoing description of the various parts of the device, the operation thereof may be readily understood. The parts of the back which have been described, that is the cover or cap and the holder may

be made of any suitable material, such as aluminum or other metal or material. The teeth likewise may be made of any suitable material, such as hard rubber, celluloid or ivory. With the arrangement described, it is only necessary to remove the cap or cover from the holder to permit of the removal and replacement of any of the teeth or of all of the teeth. These teeth may be placed in the holder readily and retained against displacement from the holder by placing the cap or cover upon the holder with the ends 9 in clamping relation to the series of teeth and in frictional contact with the remote sides of the head portions of the two end teeth.

It will thus be apparent that I provide a comb which is of simplified construction and which is more sanitary than combs ordinarily used, since the teeth thereof may be readily removed to permit cleaning thereof. Moreover, my invention effects an economy in that broken teeth of a comb may be replaced and the comb thus rendered suitable for continued use at a relatively slight cost and with the necessity of discarding the entire comb obviated.

Obviously, my invention is susceptible of embodiment in forms other than that illustrated in the accompanying drawing, and I therefore consider as my own all modifications and adaptations of the form of the device herein disclosed which fairly fall within the scope of the appended claims.

Having thus described the invention, what I claim is:

1. A comb comprising a holder having a pair of spaced parallel side strips and transverse strips connecting the side strips together at their upper edges and at the opposite ends thereof, a pair of end teeth having head portions received between said side strips at opposite ends of the holder with the upper ends of said end teeth engaging the under sides of said transverse strips, a plurality of intermediate teeth having head portions received between said side strips and arranged in series between said end teeth, a cover clampingly receiving said holder, and ends integral with the side strips and in frictional contact with the remote walls of the heads of said end teeth.

2. A comb comprising a holder having a pair of spaced apart parallel side strips connected together at their ends by transverse strips extending between the upper edge portions thereof, a pair of end teeth having head portions fitting between the side plates beneath said transverse strips, a plurality of intermediate teeth having head portions fitting between said side strips and between said end teeth, said side plates having inwardly extending lower edge portions contacting said teeth at the juncture of the head and shank por-

tions of the latter, a cover fitting upon the holder, and means spanning the ends of said side strips for engaging with said end teeth to hold all of said teeth against movement longitudinally of the holder.

3. A comb comprising a holder having a pair of spaced apart parallel side strips connected together at their ends by transverse strips extending between the upper edge portions thereof, a pair of end teeth having head portions fitting between the side plates beneath said transverse strips, a plurality of intermediate teeth having head portions fitting between said side strips

and between said end teeth, said side plates having inwardly extending lower edge portions contacting said teeth at the juncture of the head and shank portions of the latter, a holder having a body of channel-shape and being made of a material having inherent spring quality, said body being adapted to embrace the side plates, and means at the ends of the side plates for sealing the ends of the holder and for frictionally engaging with the remote walls of the heads of said end teeth.

SAMUEL MICHAUD.
